UNITED STATES PATENT OFFICE

JOHN W. BRANDT, OF ELYRIA, OHIO

CYCLE SADDLE

Application filed September 19, 1930. Serial No. 482,997.

My invention relates to saddles, and relates more particularly to saddles adapted to be used for bicycles, motorcycles, velocipedes, and the like.

5 An object of my invention is to provide a saddle of improved construction affording a high degree of comfort in use.

Another object of my invention is to provide a saddle having a novel combined reach 10 and spring member construction, dispensing with all auxiliary compression and tension springs.

Another object of my invention is to provide an improved saddle which will be simple 15 in construction, inexpensive to manufacture, and to maintain in efficient use.

Another object of my invention is to provide an improved saddle employing a minimum number of parts, which are capable of 20 being very inexpensively fabricated.

Other objects of my invention, and the invention itself, will become more apparent by reference to the following description of an embodiment of my invention illustrated in 25 the accompanying drawing, to which reference is made therein:

Referring now to the drawing:

Fig. 1 is a bottom plan view of the improved saddle of my invention, with associated clamp shown in dotted lines.

Fig. 2 is a longitudinal medial sectional view of the saddle of my invention.

Referring now to all of the figures of drawing in all of which like parts are designated 35 by like reference characters.

For the saddle shown in the drawing, and which is an embodiment of my invention, to support the seat element, a longitudinally extending reach member is provided, this 40 being in the form preferably of a single piece of steel spring wire bent into the form of a loop to provide a pair of rearwardly extending substantially parallel side arms 1 and 2. Each of the said side arms 1 and 2, 45 in turn, are bent into the form of substantially vertical loops, with an intermediate rearmost portion of each formed to provide preferably a plurality of convolutions, which form contractile spring elements 3.

50 The saddle frame preferably comprises a

sheet metal base 12, a leather or like cover 10, and upholstering material 11, enclosed between the cover and base.

While the seat 10 may be of any desired construction, I preferably provide it with a sheet metal sub-frame 12.

The reach arms 1 and 2 are integrally joined at their front ends by a yoke portion 13, which is passed through the looped clip 14, which is secured by a rivet 15 to the pommel or forward end of the saddle base 12. The loops 3 preferably comprise a plurality of convolutions, as illustrated in Fig. 1, and are provided for the purpose of imparting resiliency to the supporting reach members.

The seat is supported on the substantially U-shaped reach member, as best illustrated in Fig. 2, as comprising a pair of forwardly extending arms 1 and 4 adapted to be secured to the saddle seat by the clips 14 and 16 and having resilient means 3 at their yoke connector portion by virtue of the clip connection 14 at its intermediate forwardly disposed yoke portion 13, and the laterally extending ends 5 of the portions 4, of the reach arms 1 and 2, said portions 4 extending forwardly and upwardly from the spring convolutions 3. The reach arms are supported intermediate the yoke 13 and the convolutions 3, preferably, near the convolutions, being engaged by gripping extensions 7 and 8, of a saddle clamp 6, whereby by means of a bolt 9 the seat 10, supported by the reach member, is carried on the saddle post 20.

85 The laterally extending ends 5 of the short portions 4 of the reach arms make a hinging connection with the seat 10, by virtue of the sheet metal clips 16 secured by rivets 17 and 18 to the sheet metal base 12. Preferably, also, an intermediate steel wear piece 19 is interposed between the clip 16 and the sheet metal base to form a part of the bearing for the rotatable ends 5 of the said short arms 4 of the reach member.

90 The construction above described provides hinge connections between the reach member and the seat at the three spaced points, namely at the clip 14 and at each of the clips 16.

100 The spring mounting for the saddle of my

present invention operates in a novel mode to yield to road shocks, whereby an easier riding saddle is had. This is effected by virtue of the construction shown wherein the 5 convolutions 3 furnishing most of the spring action are supported rearwardly of the hinged ends 5 of the arms 4 which extend upwardly and forwardly therefrom, and by virtue of the fact that the portions of the 10 reach arms 1 and 2 which extend between the clamp 6, 7 and 8 and the forwardly disposed hinge end 13 of the reach element is less yieldable in the downward direction than are the hinged ends of the arms 4. 15 By virtue of this construction, upon a road shock tending to move the saddle downwardly by virtue of the weight of the rider upon it, the hinged ends 5 of the arms 4 tend to rotate about the hinged ends 13 of the reach 20 arms 1-2, substantially in the direction indicated by the dotted line terminating in the arrow *a*, Fig. 2, which substantially coact as a single reach element, even though there be some slighter bodily movement of 25 the hinged end 13 downwardly effecting a slight rotary movement of said hinged end 13 in the clip 14 acting as a bearing.

At the same time the hinged ends 5 of the arms 4 will tend to move curvilinearly about 30 the axis *z* of the spring convolutions 3, along some such line as the dotted line shown which terminates in the arrow *b* in Fig. 2.

However, by virtue of the relative rigidity of the base 12 of the saddle seat, causing it to 35 act more or less like a truss between the ends 13 and 5 of the spring reach element, as before described in the direction of the arrow *a*, there will be a rearward longitudinal thrust exerted upon the short arms 4 of the reach 40 element and this will effect a rearward and slightly downward bodily movement of the convolutions 3 to shift its axis *z* substantially as indicated by the arrow *c*, while at the same time, the convolutions will be constricted 45 by a winding up action effected by the downward movement of the ends 5 of the reach arm portions 4, which will move approximately in the direction of the arrow *d*.

I find that the spring action effected substantially as above described, as nearly as I 50 can describe it, by virtue of the operative principles involved in the construction shown and described, effects a very satisfactory and most comfortable saddle mounting spring 55 operation, and which at minimum cost of manufacture is superior to most saddle spring constructions greatly exceeding the cost thereof, and in which prior spring constructions, the spring action relied upon is merely a simple up and down movement of the saddle cantle upon resilient underlying supporting springs provided thereunder, and supporting the saddle cantle. The present 60 saddle construction provides a progressively 65 shock absorbing yieldable mount for the

saddles capable of absorbing shock, whether effective vertically or longitudinally, as when encountering rough surfaces during riding of the vehicle which the saddles mount.

It is to be noted that the ends 5 of the 70 short spring arms 4 are resiliently retained within the clip 16, and that the convolutions 3 of the spring disposed intermediate the arms 1-2 and the arms 4 reinforce the arms 4 against dislodgment of the ends 5 from the clip by inward movement of such arm ends, there being but relatively short lengths of the straighter reach arm portions provided between the convolutions and the clips 75 and clamp.

Having thus described my invention in a specific embodiment, I am aware that numerous and extensive departures may be made from my invention illustrated and described herein, but without departing from 80 the spirit thereof.

I claim:

1. In a cycle saddle, the combination of a cycle seat, a support therefor comprising a loop having a long arm and a short arm and an intermediately disposed yieldable element joining the two arms, a yieldable connector for the free ends of each of said arms joining its associated arm to the underside of the cycle seat, the connector for the longer arm 90 being disposed substantially forwardly of the connector for the shorter arm, said yieldable element disposed substantially rearwardly of both said connectors, said seat, said shorter arm and said longer arm being 95 in successive superposed relation, said seat being uppermost and said short arm being intermediate said seat and an underlying portion of the longer arm, said longer arm adapted for mounting on a saddle post and supporting the other parts of the cycle saddle thereon, said arms forming substantially the sole support for said saddle on said post.

2. In a cycle saddle, the combination of a cycle seat, a resilient support therefor comprising an intermediately disposed clamp for securing the seat by said support to a saddle post, a forwardly extending reach arm element extending from said clamp to a forward portion of the seat and hingedly connected thereto, a resilient loop having forwardly directed arms disposed substantially rearwardly of said clamp, the end of a lowermost of said arms being secured in said clamp and the end of the other arm being hingedly secured to said saddle above the clamp and substantially spaced from the forward end of the saddle, said arms forming substantially the sole support for said saddle on said post.

3. In a cycle saddle, the combination of a cycle seat, a resilient support therefor comprising an intermediately disposed clamp for securing the seat by said support to a saddle post, a forwardly extending reach arm ele-

- ment extending from said clamp to a forward portion of the seat and hingedly connected thereto, a resilient loop having forwardly directed arms disposed substantially rearwardly of said clamp, the end of a lowermost of said arms being secured in said clamp and the end of the other arm being hingedly secured to said saddle above the clamp and substantially spaced from the forward end of 5 the saddle, said loop comprising a plurality of intermediately disposed spring convolutions, said arms forming substantially the sole support for said saddle on said post.
4. A cycle saddle comprising a saddle seat, 15 a substantially resilient U-shaped seat supporting element disposed below the seat and making a yielding supporting engagement therewith by one of its arms, a clamp for clamping the other arm to a saddle post substantially below said seat engaging arm and 20 forwardly thereof, and seat supporting means secured by said clamp to said post extending forwardly therefrom and engaging the seat substantially forwardly of the said point of 25 engagement of said arm, said arms forming substantially the sole support for said saddle on said post.
5. A cycle saddle comprising a saddle seat, 30 a substantially resilient U-shaped seat supporting element disposed below the seat and making a yielding supporting engagement therewith by one of its arms, a clamp for clamping the other arm to a saddle post substantially below said seat engaging arm and 35 forwardly thereof, and seat supporting means secured by said clamp to said post extending forwardly therefrom and engaging the seat substantially forwardly of the said point of engagement of said arm, said means 40 comprising a prolongation of said other arm through said clamp, said arms forming substantially the sole support for said saddle on said post.
6. A cycle saddle comprising a saddle seat, 45 a substantially resilient U-shaped seat supporting element disposed below the seat and making a yielding supporting engagement therewith by one of its arms, a clamp for clamping the other arm to a saddle post substantially below said seat engaging arm and 50 forwardly thereof, and seat supporting means secured by said clamp to said post extending forwardly therefrom and engaging the seat substantially forwardly of the said point of engagement of said arm, said 55 U-shaped element having a relatively most yieldable portion joining its two ends, said arms forming substantially the sole support for said saddle on said post.
- 60 7. A cycle saddle comprising a saddle seat, a substantially resilient U-shaped seat supporting element disposed below the seat and making a yielding supporting engagement therewith by one of its arms, a clamp for 65 clamping the other arm to a saddle post sub-
- stantially below said seat engaging arm and forwardly thereof, and seat supporting means secured by said clamp to said post extending forwardly therefrom and engaging the seat substantially forwardly of the said point of engagement of said arm, said U-shaped element being formed from a length of wire and comprising an intermediately formed spring coil, said arms extending forwardly therefrom; said arms forming substantially the sole support for said saddle on 70 said post.
8. In a cycle saddle, the combination of a cycle seat, a resilient unitary reach and spring support therefor, comprising a loop having 75 rearwardly extending substantially parallel arm portions, an intermediately disposed clamp for securing the seat by said support to a saddle post, the portions of said arms extending from said clamp to a forward portion 80 of the seat and hingedly connected thereto at their yoke portion, and the portions of said arms extending rearwardly from said clamp, forming a resilient loop having forwardly directed arm extensions disposed substantially rearwardly of said clamp, the ends 85 thereof being hingedly secured to said saddle above the clamp and substantially spaced from the forward end of the saddle.
9. A cycle saddle comprising a saddle seat, 90 a substantially resilient unitary U-shaped seat supporting element disposed below the seat, the yoke of said U-shaped element comprising resilient means having forwardly disposed arms adapted to be secured to said seat 95 forwardly of said resilient means and a clamp for clamping one of said arms to a saddle post disposed substantially forwardly of said resilient means.
10. A cycle saddle comprising a saddle 100 seat, a substantially resilient unitary U-shaped seat supporting element disposed below the seat, the yoke of said U-shaped element comprising resilient means having forwardly disposed arms adapted to be secured to said seat 105 forwardly of said resilient means and a clamp for clamping one of said arms to a saddle post disposed substantially forwardly of said resilient means, and substantially forwardly of the point of engagement 110 of one of said arms to said seat.
11. A cycle saddle comprising a saddle seat, a substantially resilient unitary U-shaped seat supporting element disposed below the seat, the yoke of said U-shaped element comprising the relatively most yieldable portion and having forwardly disposed 115 substantially parallel arms adapted to be secured to said seat, a clamp for clamping one of said arms to a saddle post disposed substantially forwardly of said resilient means, said U-shaped element being formed from a length of wire comprising an intermediately formed spring coil, said arms extending forwardly therefrom.

12. A cycle saddle comprising a saddle seat, a substantially resilient unitary **U**-shaped seat supporting element disposed below the seat, the yoke of said **U**-shaped element comprising resilient means having a pair of forwardly disposed arms, each adapted to be secured to said seat forwardly of said resilient means.
13. A cycle saddle comprising a saddle seat, a substantially resilient unitary **U**-shaped seat supporting element disposed below the seat, said element comprising a pair of arms and an intermediate resilient yoke portion.
14. A cycle saddle comprising a saddle seat, a substantially resilient unitary **U**-shaped seat supporting element disposed below the seat, the yoke of said **U**-shaped element having a pair of arms each adapted to be secured to said saddle seat.
20. In testimony whereof I hereunto affix my signature this 17 day of September, 1930.
